UNITED STATES PATENT OFFICE.

WERNER I. STAAF, OF PITTSBURGH, PENNSYLVANIA, ASSIGNOR OF ONE-HALF TO
ROBERT A. MORROW, OF PITTSBURGH, PENNSYLVANIA.

COMBINATION GAGE-COCK, ALARM, &c.

1,084,497.

Specification of Letters Patent. Patented Jan. 13, 1914.

Application filed April 6, 1912. Serial No. 688,979.

To all whom it may concern:

Be it known that I, WERNER I. STAAF, a resident of Pittsburgh, Allegheny county, Pennsylvania, have invented a new and useful Combination Gage-Cock, Alarm, &c., of which the following is a full, clear, and exact description, reference being had to the accompanying drawings, forming part of this specification, in which—

10 Figure 1 is a side view, partly broken away, showing the application of my invention to a water column, as a high and as a low water alarm, and also as a feed water regulator; Fig. 2 is a view similar to Fig. 1, but showing the application of the invention as a feed-water regulator only; Figs. 3 and 4 are sectional views showing the device as adapted for a combination gage cock and low water alarm, the planes of the 20 two sections being at right angles to each other; Fig. 5 is a view similar to Fig. 3, but showing the device as adapted for a high water alarm; and Fig. 6 is an end view.

25 My invention has relation to combination gage cocks and high and low water alarms, and is designed to provide a simple and efficient device of this character which can be readily adapted for use either as a high 30 or as a low water alarm.

My invention also provides a device which is capable of use as a regulator for feed water pumps, etc.

The nature of my invention will be best 35 understood by reference to the accompanying drawings, in which I have shown the preferred embodiment thereof, and which will now be described, it being premised, however, that various changes can be made 40 in the details of construction and arrangement of the several parts, without departing from the spirit and scope of the invention as defined in the appended claims.

In these drawings, the numeral 2 designates 45 a water column, which is in general of the usual character, and which is shown in Fig. 1 as having a threaded boss 3 for the attachment of the high water alarm, and a similar boss 4 for the attachment of a low 50 water alarm.

The alarm device comprises a body 5 having detachable end caps 6 and 7. Secured in the end cap 6 is a bulb or similar recep-

tacle 8, which is designed to contain some fluid which will expand and contract under 55 variations in temperature. The neck portion 9 of this bulb has an opening 10 communicating with the interior of the bulb and also leading into a diaphragm chamber 11 at one side of a diaphragm 12, which is 60 held at its peripheral edges by the bolting flange of the cap 6. Attached to the diaphragm is a stem 13 which extends within the body 5 and carries a valve 14. This valve controls a port 15 in a diaphragm or 65 partition wall 16 placed within a chamber 17 in said body. One end of the chamber 17 is at all times connected with the interior of the water column by a port or passage 18 which extends through the body 5 and 70 through the cap 6. The other side of the chamber 17 communicates by a suitable pipe connection 19 with an alarm whistle 20, in the arrangement shown in Fig. 1.

The stem 13 is provided with a suitable 75 packing 22 within the body 5, this packing has a spring 23 seated against it and against an adjusting ring 24, and another spring 25 is seated between the opposite side of this ring and diaphragm 12. 80

The end cap 7 has a port 26 normally closed by a hand valve 27 and connecting one end of the chamber 17 with a blow-off 28. This blow-off 28 is shown as extending into a pipe or nozzle 29, which communicates by a port 30 with the air side of the diaphragm chamber 11. 85

Supposing the device to be arranged as a low water alarm, as in Figs. 3 and 4, the operation is as follows:—As soon as the 90 bulb 8 becomes uncovered with water and is subjected to the action of steam in the water column, the expansion of the liquid contained therein is sufficient to actuate the diaphragm 11 to open the valve 14, and 95 thereby admit steam through the port 15 and connection 19 to the alarm or whistle.

To adapt the device for use as a high water alarm, the valve 14 is shifted on the stem 13 to the opposite side of the diaphragm 16, as shown in Fig. 5. In this arrangement, when the bulb 8 is covered or partly covered with water, a contraction of the liquid contained therein will take place, and this will cause the valve 14 to 105 open the port 15 and sound the alarm.

The hand-operated valve 27 affords means for trying out the column at any time in the manner of an ordinary try-cock. When this is done, any accumulation due to leakage or condensation in the air side of the diaphragm chamber will be siphoned or drawn off at the nozzle 29 through the port 30.

The device as shown in Figs. 3 and 4 can 10 be adapted for use as a feed water regulator in the manner shown in Fig. 2. When so used, a pipe 31 is attached to the connection 19, and is extended to a device for operating a control valve in the feed water supply 15 pipe. In so far as the present application is concerned, any suitable device may be used for this purpose. I have, however, in Fig. 2, indicated a particular form of device which forms the subject-matter of a co- 20 pending application Serial No. 688,978 filed April 6, 1912. This device is shown as consisting of a cylinder 32 having a piston 33 therein below which the pipe 31 enters. The stem 34 of this piston is connected to the 25 weighted lever 35 of a control valve, which is located in the casing 36 in the feed water supply line 37. The weighted lever normally maintains its valve closed; but when the steam is admitted to the chamber 17 and 30 thence to the pipe 31, the piston 33 is actuated to open the valve and to hold it open until the water level in the column 2 is again restored to normal.

My invention may also be readily adapted 35 to control the operation of pump regulators and similar devices.

The advantages of the invention result from the simplicity of construction; from the fact that the device can be used with 40 little or no change for a variety of different purposes; that it is effective and reliable in its operation; and that it can be manufactured and sold at a relatively low cost. It also does away with the use of floats and 45 float-operated connections such as are usually employed in devices of this character, and which are open to various objections.

What I claim is:—

1. In a device for actuating high and low 50 water alarms and feed-water regulators, the combination with a water container and with a device to be operated, of a controlling device comprising a casing having means for its attachment to the container and also 55 having a steam escape passage opening into the interior of the container and also connected with the device to be operated, a valve for controlling the passage of steam from the container through said passageway 60 to the device to be operated, a diaphragm chamber in the casing, a diaphragm in said chamber, an actuating connection between the diaphragm and the valve, and thermo-

static means carried by the casing and adapted to cause the actuation of the diaphragm; substantially as described.

2. The combination with a water container, of a casing connected thereto and containing a diaphragm chamber, a diaphragm in said chamber, a valve connected to said diaphragm to be actuated thereby, said valve controlling a port or passage which leads from the interior of said container into and through the casing, and a receptacle for containing an expansion fluid, 70 said receptacle being secured to and projecting from the casing into the interior of the container and having its interior communicating with the diaphragm chamber at one side of the diaphragm, the casing having 75 a vent port leading from the opposite side of the diaphragm chamber, substantially as described.

3. In a device for actuating high and low water alarms and feed-water regulators, the 85 combination with a water container and with a device to be operated, of a controlling device comprising a casing having means for its attachment to the container and also having a steam escape passage opening into 90 the interior of the container and also connected with the device to be operated, a valve for controlling the passage of steam from the container through said passageway to the device to be operated, a diaphragm 95 chamber in the casing, a diaphragm in said chamber, an actuating connection between the diaphragm and the valve, and a bulb-like receptacle connected to the casing and projecting within the container, the space 100 within said receptacle communicating with the diaphragm chamber and being designed to be filled with an expansible fluid; substantially as described.

4. The combination with a water container, of a device for indicating or controlling the water level in said container, said device comprising a casing having means for its attachment to the container, the casing also having a steam passage leading therethrough from the interior of the container and communicating directly with the interior of the container at one end, a valve for controlling said passage, a device connected to the outlet end of said passage 115 to be operated by the steam escaping therethrough when the said valve is opened, and means controlled by the water level in the container for actuating the valve, substantially as described.

5. The combination with a water container, of a device for indicating or controlling the water level in said container, said device comprising a casing having means for its attachment to the container, the casing also having a steam passage lead-

ing therethrough from the interior of the container and communicating directly with the interior of the container at one end, a valve for controlling said passage, a device connected to the outlet end of said passage to be operated by the steam escaping therethrough when the said valve is opened, a diaphragm in the casing connected to the valve, and thermostatic means carried by

the casing for actuating the diaphragm, substantially as described.

In testimony whereof, I have hereunto set my hand.

WERNER I. STAAF.
